BUCKLE FOR METAL BAND TIE STRAP

Archibald Edgar McElroy, 997 Skipack Pike,
Blue Bell, Pa. 19422

Filed Dec. 21, 1966, Ser. No. 5,145

Term of patent 14 years

(Cl. D54—1)

I claim:

The ornamental design for a buckle for metal band tie strap, as shown.
